[57] CLAIM

The ornamental design for a combined digital audio disc player, radio tuner, amplifier and tape recorder, as shown and described.

DESCRIPTION

FIG. 1 is a perspective view of a combined digital audio disc player, radio tuner, amplifier and tape recorder showing our new design in a state where the disc tray is drawn out and the cassette lid is opened;

FIG. 2 is a left side view thereof where the disk tray and the cassette lid are closed;

FIG. 3 is a front view thereof;

FIG. 4 is a right side view thereof;

FIG. 5 is a rear view thereof;

FIG. 6 is a top view thereof;

FIG. 7 is a bottom view thereof; and,

FIG. 8 is a front view thereof with power turned on.

The broken line showing of numbers in FIG. 8 is for illustrative purposes only and forms no part of the claimed design.
